UNITED STATES PATENT OFFICE.

HUBERT CARLISLE RAY, OF VISALIA, CALIFORNIA.

CARBURETER FOR EXPLOSIVE-ENGINES.

SPECIFICATION forming part of Letters Patent No. 659,987, dated October 16, 1900.

Application filed August 2, 1899. Serial No. 725,886. (No model.)

To all whom it may concern:

Be it known that I, HUBERT CARLISLE RAY, of Visalia, in the county of Tulare and State of California, have invented a new and Improved Carbureter for Explosion-Engines, of which the following is a full, clear, and exact description.

My invention relates to an improvement in devices for producing gas from oils, and is designed for use in connection with explosion-engines, the object of the device being to enable crude oils to be used instead of refined petroleum or gasolene.

My invention comprises the novel features which are hereinafter described and claimed.

Reference is to be had to the accompanying drawing, forming a part of this specification, in which the figure shows the upper or cylinder end of a gas-engine having my device attached thereto, the carbureter being shown in section.

My device is herein shown as applied to a vertical gas-engine, although the method of its attachment may be widely varied according to the circumstances of each particular case, yet the principle of this application is sufficiently illustrated.

In the drawing, A represents the cylinder of the gas-engine, and B the pipe through which the exhaust or waste gases from the engine are discharged. This pipe is provided with an extension C, which passes centrally through a carbureting-chamber or oil-tank E, which is located above the engine-cylinder. This carbureter or oil-tank is supplied with a certain amount of oil, which is ordinarily sufficient to only partially fill the tank. Oil is supplied to this tank from a reservoir or tank G, which is located at any convenient and safe point and at a slightly-greater elevation than the point where it is desired to maintain the oil in the carbureter E. This tank G is connected with the carbureter by means of a pipe I, which is provided with a check-valve I' and an ordinary throttle-valve I². The carbureter may be provided with a gage-glass e, which will indicate the exact level of oil therein. The suction through the pipe F will draw oil through the valve I', which latter can be set to regulate the amount of oil entering the carbureter.

A pipe D has the lower end D² thereof extending upward within the exhaust-chamber B of the engine and connecting with the outer air by a side opening d', and by this means 55 the air passing through the pipe D² is heated. The upper end of the pipe D preferably extends slightly above the top of the carbureter-tank, forming a curve or bend d, the end D' extending downwardly within said 60 tank and terminating near the bottom thereof and below the level of the oil therein, so that air passing through the pipe D bubbles up through the oil and becomes charged with the vapors of the oil. The exhaust passing 65 upwardly through the pipe C and the carbureter heats the contents thereof, so that the oil becomes very volatile, and the air passing upwardly through the same becomes heavily charged. The constant agitation of the oil 70 caused by the air passing through it makes it give off easily all its volatile parts, and the agitation also prevents caking from heat of the residue in the carbureter; also, the hot air helps to heat the oil. This charged air is 75 drawn off through a pipe F, the upper end of which preferably lies within an upward extension E' of the tank, so as to make sure that none of the oil will be drawn through into this pipe. The pipe F extends down- 80 ward and connects with the supply-passages of the engine. The upper portion of the carbureter E is connected with the reserve-tank G by means of a pipe H, which is provided with a check-valve h at any convenient point, 85 preventing flow of air or oil from the reserve-tank to the carbureter through this pipe. If the oil in the carbureter should become excessively heated and an amount of gas should thereby be generated greater than is being 90 used, the surplus gas will pass through the pipe H to the reserve-tank, and as the end of the pipe H extends beneath the level of oil in said tank the gases will be forced to bubble up through the oil, and as this tank is located 95 where it will be kept cool the gases will be condensed and no loss will occur. This forms a safety device to prevent generation of excessive pressure.

A pipe F' is connected with the pipe F and 100 is provided with a throttling-valve f, by means of which connection may be made with a sup-

ply of gas or gasoline for operation in the ordinary manner when the engine is first started.

In operating an engine having my device attached thereto it will be necessary, if crude oil is being used, to operate the engine a short time before the carbureter is brought into use. For this purpose the pipe F' is supplied and ordinary gas or gasoline, which will vaporize readily, is first used. After the engine has been running a short time and the exhaust has heated the oil in the carbureter the valve f is closed and the supply of explosive mixture is drawn from the carbureter E.

15 A valve J is connected with the bottom of the carbureter, so that the residue and heavier portions of the oil left after volatilizing the lighter portions may be drawn off and the carbureter cleaned.

20 With this device it is possible to use crude petroleum and other similar hydrocarbons, thus materially reducing the cost of fuel.

Having thus fully described my invention, I claim as new and desire to secure by Letters

25 Patent—

1. A carbureter for explosive-engines, comprising a carbureting-tank, means for heating said tank, an oil-supply tank connected with said carbureting-tank, and a pipe leading from the gas-space of the carbureting-tank to the oil-supply tank, said pipe being provided with a safety-valve, substantially as set forth.

2. A carbureter for explosion-engines, comprising an oil-tank having passages therein for receiving the engine exhaust whereby its contents are heated, an air-supply pipe hav-

ing its discharge end projecting beneath the oil in the tank and its other end drawing air through passages heated by the engine, an engine-supply pipe extending from the top of said tank, and an oil-supply tank having an oil-feeding pipe connected with the carbureter and provided with a back-pressure valve, and a pipe leading from the top of the carbureter to beneath the oil in the supply-tank and provided with a safety-valve, substantially as described.

3. A carbureter for explosion-engines, comprising an exhaust-heated carbureting-tank, and engine-heated air-supply discharging beneath the oil in the carbureter, an engine-supply pipe connecting carbureter, and engine, and a combined oil-supply and surplus-gas condenser, consisting of a tank having a pipe for conveying oil to the carbureter, and a pipe leading from the gas-space of the carbureter to beneath the oil-level in the supply-tank and provided with a safety-valve, substantially as specified.

4. A carbureter for explosive-engines, comprising a carbureting-tank arranged to be heated by the products of combustion of the engine, an oil-supply tank and condenser connected with the lower part of said carbureting-tank, and a pipe leading from the top of the carbureting-tank to beneath the oil in the supply-tank and condenser and provided with a safety-valve, as set forth.
